SIDNEY TRIVICK, OF CLAPHAM, ENGLAND.

PROCESS OF MAKING DRY ALKALINE SULFATES.

SPECIFICATION forming part of Letters Patent No. 728,335, dated May 19, 1903.

Application filed June 7, 1902. Serial No. 110,689. (No specimens.)

To all whom it may concern:

Be it known that I, SIDNEY TRIVICK, of No. 2 Lydon road, Clapham, in the county of Surrey, England, have invented a Process of Making Dry Alkaline Sulfates, of which the following is a specification.

This invention relates to a process for the manufacture of a salt of one or more of the alkali metals which contains not less than four chemical units of sulfuric anhydride to one unit of the oxid of the alkali metal and which salt is associated with not more than three chemical units of water of crystallization.

It consists in adding to concentrated sulfuric acid a quantity of a salt of one or more of the alkali metals which has previously been rendered completely anhydrous, subjecting the mixture for some time to a temperature not exceeding 250° centigrade, and a subsequent treatment of the product to a drying process whereby a large proportion of the water of crystallization is extracted.

As a representative example I will describe in detail the process as carried out when the alkali salt consists of common salt—chlorid of sodium. This salt is first heated until it is rendered completely anhydrous. A quantity of concentrated sulfuric acid is then placed in a vessel capable of withstanding the action of the heated acid, and arrangements are provided for heating the vessel and withdrawing its contents, and for collecting and condensing, when desired, the volatile products given off in the process. An apparatus such as is used in the production of hydrochloric acid would serve the purpose of this operation. Such an apparatus is illustrated in the accompanying drawings, in which—

Figure 1 is a vertical section. Fig. 2 is a section taken along the broken line 2 2 of Fig. 1. Fig. 3 is a sectional plan taken along the line 3 3 of Fig. 1, in which the pan *a* is supposed to be removed for the purpose of exhibiting the flues.

In the views, *a* is a cast-iron pan, the flange of which rests on the upper edge of the external wall of an annular flue-passage *b*, the inner wall of which is somewhat cone-shaped and supports the body of the pan. The fuel is burned in the body *c*, and the products of

combustion pass through apertures *d d*, provided in the arch which forms a continuation of the furnace. They emerge into the space below the center of the pan and proceed along the annular flue in the direction shown by the arrows and escape to the chimney by an opening which is indicated in Fig. 3 by the dotted lines *ee*. The pan is charged through the opening *f*, the lid *g* being removed and the sloping hinged door *h* lowered. The concentrated sulfuric acid is first supplied by a pipe which is afterward withdrawn, and then the appropriate quantity of anhydrous salt is placed on the sloping door *h*, which at this time is closed, and then the lid *g* is replaced. By opening the door *h* at intervals to a small amount only by means of the weighted lever *k* the salt is fed into the acid in a gradual manner.

If the salt is chlorid of sodium, there will be an abundant evolution of hydrochloric-acid gas, which will escape through the pipe 1 to a condenser, the hydrochloric acid being a by-product. The heat evolved in this operation is sufficient to raise the temperature of the mixture to the required degree without the aid of external heat; but it is advantageous to employ some external heat to maintain the molten condition. When "niter cake" is used or other salts, external heat is essential to the process. The temperature to which the mixture is subjected is short of that which will cause the evolution of sulfuric-acid fumes, which is about 250° centigrade.

When the operation is completed, a vessel mounted on wheels is run in through the doorway *m*, so as to be below the center of the pan. The plug *n* is then withdrawn and the pan emptied of its contents, the salt being then in the molten state.

If allowed to cool at rest, it will produce a nearly-transparent crystalline mass consisting of tetra-sulfate of sodium, together with other higher sulfates of the same metal.

If the sodium chlorid employed is in a perfectly-pure and anhydrous condition and the sulfuric acid has a degree of concentration represented by one hundred per cent., the proportion of the weight of the former to the latter requisite to complete the reaction and

form the tetra-sulfate simply will be 29.8 per cent., for the equation which expresses the reaction is

- 5 The HCl is evolved as vapor, and the product left in the vessel has a composition in which the combining elements may be regarded as grouped, so as to form sodium oxid, (Na_2O), 10 sulfuric anhydrid, (SO_3), and water, (H_2O), in which, combined with one chemical unit of Na_2O , there are four chemical units of SO_3 , and these are associated with three units of water of crystallization.
- 15 In practice it would be desirable to use a smaller proportion of chlorid on account of the probable loss of some of the H_2SO_4 in the subsequent heating and also to provide for the formation of sulfates higher than the 20 tetra-sulfate.

The molten product is well stirred while it is cooling, so as to produce a granulated mass with a large extent of surface. This is exposed to a current of warm air. To facilitate 25 this operation, the granulated mass may advantageously be placed in a revolving cylinder, by which means continually-fresh surfaces will be presented to the warm atmosphere and the extraction of the water of crystallization rendered rapid. By such means 30 I am able to produce a very portable dry salt from which by the addition of water I am able to derive the benefit due to a supply of strong sulfuric acid without having to incur the danger due to its transport.

35 If Nordhausen or fuming sulfuric acid is used, a larger proportion of sulfates higher than the tetra-sulfate will be secured in the product; but in this case the heating must be 40 carefully regulated, so as to avoid as much as possible the loss due to the escaping fumes of sulfuric acid.

In the case in which the alkali salt used is 45 chlorid of sodium the subsequent heating is not essential for the formation of tetra-sulfate merely. Heating to a moderate degree appears to encourage the formation of still higher sulfates.

To produce the higher sulfate of potassium 50 in a similar way, probably the most advantageous potassium salt to add to the sulfuric acid would be so-called "niter cake," which in the pure anhydrous condition would be represented by K_2SO_4 . The chemical reaction 55 which in this case would take place if only the tetra-sulfate were formed may be represented by the equation

60 so that the proportions requisite for the complete reaction would be 59.2 of K_2SO_4 to 100 H_2SO_4 . In practice the proportion of the former should be less for the same reasons as those mentioned in the case of sodium.

65 In the case of potassium salts the reaction should be stimulated by heating during the mixing process. The granulated potassium

product on being exposed to warm air behaves in a similar manner to the sodium salt and parts with a large quantity of its water 70 of crystallization. It may be observed that in the two cases cited in which NaCl and K_2SO_4 are used for mixing with the concentrated sulfuric acid the quantity of the salt of the alkali metal which is required to effect 75 the tetra-sulfate reaction is such that there shall be one chemical unit of the alkali metal itself introduced into the mixture for every two chemical units of sulfur which it contains, including the sulfur, if any, which is 80 added with the salt. This condition is required to be satisfied whatever be the salt of alkali metal which is used.

On attempting to similarly produce ammonium tetra or higher sulfates, a somewhat 85 gelatinous mass is formed when cold. Therefore for the purpose of obtaining a dry salt as the final product it will be advantageous to add some sodium or potassium salt with the ammonium salt to the sulfuric acid, and 90 thus obtain a double or treble tetra-sulfate compound mixed with higher sulfates which, with sufficient sodium or potassium, will granulate and subsequently readily part with its water of crystallization in the drying process. A double salt of sodium and potassium 95 without ammonium may correspondingly be formed.

I claim—

1. A process for the production of a dry 100 salt composed of one chemical unit of an oxid of an alkali metal chemically united with not less than four units of sulfuric anhydrid and associated with not more than three chemical units of water consisting in adding to concentrated sulfuric acid, H_2SO_4 free from water, such a quantity of an anhydrous salt of the alkali metal as will contain half as many chemical units of the metal itself as there will be of sulfur in the mixture, heating the 105 mixture to a temperature not exceeding 250° centigrade granulating the mass by stirring while cooling and subsequently exposing it to a current of warm dry air, substantially as described.

2. A process for the production of a dry 110 salt composed of Na_2O chemically united with not less than four units of SO_3 and associated with not more than three units of H_2O consisting in adding to concentrated sulfuric 115 acid, H_2SO_4 free from water, such a quantity of anhydrous salt of sodium as will contain half as many chemical units of sodium as there will be sulfur in the mixture, heating the mixture to a temperature not exceeding 250° centigrade granulating the mass by stirring while cooling and subsequently exposing it to a current of warm dry air, substantially as described.

3. A process for the production of a dry 120 salt composed of Na_2O chemically united with not less than four units of SO_3 and associated with not more than three units of H_2O , consisting in adding to one hundred parts of con-

centrated sulfuric acid, H_2SO_4 free from water, nearly thirty parts of anhydrous sodium chlorid, heating the mixture to a temperature not exceeding 250° centigrade granulating the mass by stirring while cooling and subsequently exposing it to a current of warm dry air, substantially as described.

4. A process for the production of a dry salt composed of Na_2O chemically united with not less than four units of SO_3 and associated with not more than three units of H_2O , consisting in adding to concentrated sulfuric acid, H_2SO_4 free from water, such a quantity

of anhydrous salt of sodium as will contain half as many chemical units of sodium as 15 there will be of sulfur in the mixture, granulating the mass by stirring while cooling and subsequently exposing it to a current of warm dry air, substantially as described.

In witness whereof I have hereunto set my hand in the presence of two witnesses.

SIDNEY TRIVICK.
